DEVICE FOR GUIDING WEBLIKE MATERIAL

Karl Gösta Wester, Stockholm, Sweden, assignor
to A.B. Svenska Eläktfabriken, Stockholm, SwedenApplication October 23, 1950, Serial No. 191,514
In Sweden October 21, 1949

3 Claims. (Cl. 26—54)

1

The present invention relates to new and useful improvements in drying machines for web-like material, and more particularly to new and useful improvements in apparatus operable to direct or guide the web-like material into the drying machine and position it in the proper transverse relation with respect to the dryer.

When introducing cloth, paper or other web-like material into a dryer it is important that the web is properly guided at the entrance of the dryer in order to be positioned correctly with respect to the tenter chain or tenter pins which carry the web through the dryer. Prior to the present invention, in machines of this type, a pair of controllers have been positioned at opposite sides of the web being fed to the dryer which control the transverse movement of feeding arms that in turn feed the web to the tenter frame. In front of the pair of controllers adjacent the feed end of the drying machine edge straightening elements are provided which consist of two or more spirally threaded rolls or brushes mounted on guide arms operable to be moved transversely with respect to the direction of movement of the web. In prior machines the edge straightening elements and controllers have each been mounted on the feeding arms which are pivotally mounted to the dryer frame for lateral movement in order to follow the edge of the web-like material. By this construction the edge straighteners are afforded greater transverse movement than the controllers or control elements, and hence it is necessary that the control elements be moved transversely in order to contact the edge of the web material and thereby cause further movement of the straightening elements. This produces a hunting effect which causes the side movements of the feeding arms, control elements and edge straighteners to be greater than the distance which is normally determined by the variations of the edges of the web-like material being fed to the dryer.

With the foregoing in mind the principal object of the present invention is to provide novel apparatus which eliminates this hunting effect of the control elements and edge straighteners caused by variations in the width of material fed to the dryer. According to the invention, two standard feeding arms are provided between which the web-like material is conducted and control elements are disposed adjacent the forward ends of the feeding arms at opposite sides of the web-like material to produce impulses for changing the distance between the feeding ele-

2

ments. In addition, edge straighteners are provided in front of the feeding arms and control elements for straightening the edge of the material being inserted into the drying machine. The edge straighteners are arranged on separate supports and are interconnected with the feeding elements by means of an adjustable loose or resilient connection affording limited relative lateral movement between said support and feeding arms to thereby prevent the support from following minor movements of the feeding arms caused by slight variations in the edge of the material being fed to the dryer. At the same time, however, a relatively large transverse movement of the feeding arms will impart similar movement to the edge straighteners and control elements.

The invention will now be more fully described in connection with the embodiment of the invention illustrated in the accompanying drawings, in which:

Fig. 1 is a side elevational view of the feed end of a dryer made in accordance with the present invention;

Fig. 2 is a fragmentary plan view of the feed end of the dryer illustrated in Fig. 1; and

Fig. 3 is an enlarged fragmentary plan view partially in section illustrating the loose or resilient connection between the support for straightening elements and the feeding arms.

Referring more specifically to the drawing, reference numeral 1 designates generally the web-like material which is fed into the dryer. The material 1 is passed over a roll 2 and between a plurality of edge straighteners 3, 4 and 6 in the manner illustrated in Fig. 1. The edge straighteners 3, 4 and 6 rotate continuously and are provided alternatively with right and left hand threads which cause the edge of the material passing therebetween to be straightened in conventional manner. A drive motor (not shown) carried in a box-like support 5 continuously rotates the straightening elements 3, 4 and 6. The support 5 is mounted for transverse movement with respect to the direction of movement of the web material 1, for example, by means of wheels 15 and 19 which engage a pair of transverse guides or rails 17 and 18.

Pivoted adjacent the forward end 50 of the dryer and extending forwardly therefrom to the inner end of the straightening elements is a pair of feeding arms 10, 10 which are adapted to be pivoted in opposite directions perpendicular to the path of travel of the web about axes 20, 20. The feeding arms 10, 10 are par-

tially broken away in Fig. 2 and consequently the rotation of the feeding arms will in fact take place about a greater radius than that shown in Fig. 2. Positioned inwardly adjacent the straightening elements is a pair of relay boxes 7, 7 each of which contains a pair of switches (not shown) operable to control operation of a reversible motor in the usual manner which pivots its associated feeding arm. Depending downwardly from each of the relay boxes 7, 7 is a controller or feeler element 8, 8 which is adapted to be engaged by the edge of the web 1 and moved transversely by the variation in the transverse position of the edge of the web. Each controller element controls operation of the switches in its associated relay box.

The side edges of the web material are engaged and grasped at the forward ends of the feeding arms by the usual tenter clamps or tenter pins arranged on endless conveyors, the forward ends of which are carried by the feeding arms. These clamps convey the material into the drying machine in the direction shown in Fig. 1. The tenter clamps are of conventional type and thus are not shown in the drawings. It is important, therefore, that the feeding arms may be pivoted rapidly about their axes independently of each other to follow the variations in the transverse width of the web 1. For this reason, each of the control elements 8 controls the operation of a reversible motor (not shown) by means of the switches in the relay boxes and cause rotation of the feeding arms back and forth respectively in relation to a particular normal position. For example, each control element 8 is adapted to engage two switches in its associated relay box 7. When a control element is moved outwardly from the center line of the web it closes one of the switches and causes operation of the motor in the direction which moves the feeding arms away from the midpoint of the web. In a similar manner, actuation of the control element in the opposite direction reverses the operation of the motor and moves the feeding arm toward the midpoint of the web.

In accordance with the present invention means are provided for interconnecting the edge straighteners 3, 4 and 6 with the feeding arms 10, 10 to cause the edge straighteners to move transversely of the web along with the feeding arms. However, it is desirable to prevent movement of the edge straighteners when the feeding arms are only moved a slight distance due to small variations in the transverse width of the web in order to prevent a hunting effect in the operation of the machine. This is accomplished by providing a loose connection joint 9, 9 between the support boxes 5, 5 and the feeding arms 10, 10. This loose connection is illustrated in Fig. 3 and interconnects the extreme forward end of the feeding arms 10 with the rear surface of the supports 5. The feeding arms 10 each have a projecting pin or guide 23 extending outwardly from the forward end thereof which is engaged in an oval aperture 22 formed centrally of a bracket 22a mounted on each support 5. The joints 9, 9 are adjustable by means of two bolts 21 and 24 threaded into the bracket 22a at opposite sides of the aperture 22.

By this construction it is possible to limit

transverse movement of the edge straighteners in response to the movement of the feeding arms 10, 10 and thereby limit the hunting effect which is prevalent in the usual dryers of this type.

5 What I claim is:

1. In apparatus for guiding web-like material comprising, a pair of feed arms pivotally mounted for independent lateral movement, a support carriage mounted endwise adjacent each feed arm for movement in opposite directions transversely of the direction of travel of the material, straightening means for the edges of the material comprising groups of drive rolls mounted on each of said support carriages and arranged to engage the adjacent edge portion of said material, and a loose connection between each of said feed arms and adjacent support carriages providing limited freedom of lateral movement of each feed arm relative to said adjacent support carriage so that lateral movement of the feed arms within the limits of said loose connections is not imparted to the adjacent support.
2. In apparatus for guiding web-like material comprising, a pair of feed arms pivotally mounted for independent lateral movement, a support carriage mounted endwise adjacent each feed arm for movement in opposite directions transversely of the direction of travel of the material, straightening means for the edges of the material comprising groups of drive rolls mounted on each of said support carriages and arranged to engage the adjacent edge portion of said material, control means engageable by the opposite side edges of the material for effecting lateral movement of said feed arms in response to variations in the transverse position of the edges of said material, and a loose connection between each of said feed arms and adjacent support carriages providing limited freedom of lateral movement of each feed arm relative to said adjacent support carriage so that lateral movement of the feed arms within the limits of said loose connections is not imparted to the adjacent support.
3. Apparatus as claimed in claim 1 wherein the loose connection between each feed arm and support carriage comprises a projecting element carried by one of said members and a ring element of greater lateral dimension than said projecting element carried by the other member, the said projecting element having its end portion extending freely into the ring element, and said ring having therein elements selectively adjustable to predeterminedly limit freedom of lateral movement of the projecting element within the ring element.
